UNITED STATES PATENT OFFICE.

HANS J. ZIMMERMANN, OF CHICAGO, ILLINOIS, ASSIGNOR, BY MESNE ASSIGNMENTS,
TO R. STUTZKE COMPANY, A CORPORATION OF ILLINOIS.

SPRAY DESICCATION APPARATUS.

1,426,030.

Specification of Letters Patent. Patented Aug. 15, 1922.

Application filed October 25, 1918. Serial No. 259,655.

To all whom it may concern:

Be it known that I, HANS J. ZIMMERMANN, a citizen of Germany, residing at Chicago, in the county of Cook and State 5 of Illinois, have invented a new and useful Spray Desiccation Apparatus, of which the following is a specification.

The present invention relates to improvements in apparatus for carrying on the process of spray desiccation and will be fully understood from the following specification, taken in connection with the accompanying drawings, in which—

Fig. 1 is a longitudinal vertical section 15 through a superheated vapor desiccation apparatus; Fig. 2 is a transverse section through the circulating fan thereof; and Figures 3, 4 and 5 are, respectively, longitudinal sections through various modified 20 forms of the apparatus.

Referring first to the construction shown in Figures 1 and 2, there is illustrated a vertical cylindrical drying chamber, designated 10, having a frusto-conical shield 25 11 at the upper end, which terminates short of the upper head of the chamber to leave an annular inlet 12. The spray nozzles, of which three are diagrammatically illustrated, project downward through the upper 30 head, terminating in spray orifices at the approximate level of the shield 11.

The lower end of the cylindrical chamber 10 forms a conical hopper 13, which is reduced in diameter to such an extent that it 35 may form a central inlet for a centrifugal circulating fan 14, the shaft 15 of which is co-axial with the cylinder 10. The housing of the fan 14 is of the usual spiral or volute form, as shown in Fig. 2, and communicates 40 with a duct 17, preferably rectangular in cross-section and having a curved axis which represents in effect a continuation of the spiral curvature of the casing 16 of the fan. The duct 17 forms the tangential inlet of a 45 cyclone collector 18 which is vertically disposed in close proximity to the fan. The outlet for the collected solids from the cyclone collector 18 is located at the base of the latter, as shown at 19.

50 The vapor or gas outlet from the collector is represented at 20, being in the usual location, that is, co-axial with the collector and depending a considerable distance into the latter. The cyclone outlet conduit 20 is 55 shown as provided with two vertically dis-

posed baffles 21, pointed on the bottom and arranged at right angles to one another, as is common practice in this art. At 22 there is shown the connection of a vapor outlet pipe which serves to release vapors from the system to maintain a constant pressure therein, as will subsequently appear. Above this pipe the conduit 20 is flared as at 23 to connect with a tubular superheater, the vertical tubes of which are fastened in 60 horizontal tube sheets 24. The space surrounding the heating tubes is supplied with a heating fluid; for example, steam under pressure, by a pipe 25, the condensate being withdrawn at the base through the pipe 26. 70 Above the upper tube sheet 24 there is arranged an upwardly inclined duct 27, which communicates with the annular chamber around the shield 11 and thence with the annular inlet 12 of the drying chamber. 75

The entire apparatus described, with the exception of the shaft 15 of the blower or circulating fan and the upper head of the drying chamber, is enclosed by a heat insulating housing 28, which may be formed 80 of any suitable insulation material, such as cork or magnesia.

The apparatus above described operates according to the method disclosed in the patent to Richard W. G. Stutzke, No. 1,215, 85 889, issued Feb. 13, 1917. In brief, the liquid to be treated is introduced under considerable pressure through the spray nozzles at the top of the drying chamber and there 90 mingles in finely divided form with the descending current of the superheated vapor of the liquid menstruum. For example, in the case of an aqueous sugar solution the finely divided droplets will be enveloped in a descending current of superheated steam. 95 As this current moves toward the bottom of the drying chamber the liquid content of the droplet will be evaporated and the resultant fine solid particles will travel along in suspension in the descending steam current. 100 In the base of the drying chamber this current will be contracted in cross-section and simultaneously accelerated in velocity as it enters the central axial inlet of the fan 14. By the action of the latter the direction of 105 the current will be changed at right angles to its former course and simultaneously a very considerable centrifugal force will be brought into play as the current of steam and suspended solids traverses the fan and 110

follows the casing 16 thereof. As the result of this centrifugal action there will be effected within the fan itself a marked separation between the solids and the steam current, these solids closely hugging the wall of the casing 16. As the mixed stream passes out of the fan the centrifugal action is maintained by the curved conduit 17, the separated solids following the outer wall of 5 this curved passage until they are discharged into the cyclone collector 18. Within 10 this collector the work of separation is completed, the efficiency of the separation being very much higher than in the case of 15 an ordinary cyclone collector of the same size and design, owing to the fact that the fan itself and the delivery conduit from the fan to the cyclone is of such form as to accomplish an initial separation which is maintained up to the time of admission of the 20 stream to the cyclone.

The separated solid constituents of the liquid under treatment are released from the bottom of the cyclone while the steam 25 passes out of the central inlet 20 thereof and thence to the superheater. A mass of steam corresponding to that introduced in the form of water by the nozzles 12 will be continuously vented through the outlet 22 30 so that the pressure within the system will remain constant. In its passage through the tubes of the superheater the circulating steam current will again be brought to its initial temperature, and guided by the inclined conduit 27, will be introduced with 35 a minimum of resistance into the upper end of the drying chamber 10.

It is to be particularly noted with respect to the arrangement of the apparatus above 40 described that the various elements thereof, i. e., the drying chamber, fan, collector and superheater, are disposed in such relative positions as to operate most advantageously. Thus, since the drying chamber is vertical, 45 there is no tendency for the liquid which is introduced to be deposited on the walls thereof nor for the solids resulting from the treating of the liquid to be so deposited. On the contrary, the action of gravity on the 50 liquids and dried solids merely serves to keep them in suspension in the descending steam current and to carry them to the inlet of the fan, it being noted that this inlet is centrally arranged and co-axial with respect 55 to the drying cylinder. Change of direction of the flow which is inherent in the centrifugal blower or fan illustrated is made to serve the purpose of directing the circulating current horizontally, as is required for 60 its tangential entry into a vertically disposed cyclone collector. It is to be further noted that the separating effect of the fan is maintained by the curved conduit 17. The cyclone collector, being like the centrifugal 65 fan an instrument which inherently changes

the direction of flow, it therefore becomes possible by the arrangement described to employ a straight extension of the cyclone outlet 20 as the upwardly leading return conduit for the circulating current. The 70 tubular superheater described constitutes a part of this return conduit and performs its functions without changing the direction of flow.

It will therefore be noted that with the 75 exception of the inclined duct 27 connecting the space above the superheater with the top of the drying chamber, the whole of the circulating system described may be called a "natural" circulation, that is, there are no 80 elbows or right-angle conduits employed for the purpose of connecting the various essential elements of the system, these elements themselves being instead so related that they form in effect a circulatory system. Not 85 only does this arrangement reduce to an absolute minimum the power required for maintaining circulation through the system, prevent deposition of solids at any point save in the collector and increase the efficiency 90 of the latter, but there is secured another highly important result, which is that of compactness, it being possible to house the entire circulatory system within a single heat insulating casing, of minimum superficial area.

In Fig. 3 I have illustrated a modification of the apparatus described in the foregoing, this modified apparatus being arranged for the direct firing of the superheater. This 100 is accomplished by the use of a Dutch oven 30, which is built on one side of the tubular superheater, communicating therewith by a flue 31, which lies near the upper tube-sheet 24¹. An outlet flue 32 on the opposite side 105 of the superheater and near the lower tube-sheet thereof is connected with a jacket chamber 33 which surrounds the drying chamber 10. A chimney 34, which lies parallel with the drying chamber, has upper 110 and lower flues 35, 36, each in communication with the jacket chamber 33. A damper 37 arranged in the chimney between these two flues may be used to control the heating of the jacket 33. Thus with the damper 115 in the closed position the combustion gases from the Dutch oven 30, after traversing the superheater, must pass through the entire length of the jacket 33 before they may escape into the chimney through the upper 120 flue 35. On the other hand, if the damper 37 be opened, a direct passage for the combustion gases is afforded around the bottom of the drying chamber 10 and by the flue 36 to the base of the chimney.

In the construction of Fig. 3 I have illustrated the circulating fan and cyclone collector as being separately lagged or insulated instead of being included within a common insulation housing.

In Fig. 4 I have illustrated a further modification of the invention which is particularly designed for use with a desiccation system not employing the superheated vapors of the liquid as a drying medium. This system is identical in arrangement with that of Figure 1, save that a heat-exchange apparatus is inserted between the cyclone collector and the heater proper. This heat-exchange apparatus comprises a barrel-shaped housing 40 which forms a continuation of the cyclone outlet 20 and having therein a pair of horizontal annular tube sheets 41 connected by three concentric rows 15 of tubes 42. The lower tube-sheet 41 is of less diameter than the housing 40, while the upper tube-sheet is of the same diameter as the upper end of the housing. A conical deflector 43 is secured to the lower tube-sheet 20 41 and another deflector 44 of greater conicity to the upper tube-sheet. The cooling coil 45 occupies the space between the deflector 44 and the tubes 42, being provided with pipe connections for the circulation 25 of a cooling fluid. The lower cone 43 serves as a catch-basin for liquid condensate and has a drain-pipe 46 tapped into its lower end to carry off such condensate. The drain outlet may be protected by a conical deflector 30 47 having drainage holes near its periphery, as illustrated.

Above the heat-exchange apparatus described in the foregoing there is mounted a heater, which may be of the same construction 35 as the superheater described in connection with Figure 1.

The operation of the apparatus illustrated in Fig. 4 is as follows. Assuming that an indifferent gas, such as air, occupies the circulatory system, and that liquid to be desiccated is introduced into the drying chamber as described, such air will become partially cooled and laden with the vapors of the liquid before it escapes from the drying 45 chamber. The dried solids having been precipitated out in the cyclone collector, this more or less cooled or saturated air current enters the heat-exchange apparatus, passes between the three concentric rows of tubes 50 42, being there partially cooled, and is deflected by the cone 44 over the pipe-coil 45, where it is further cooled and a portion of the vapors which it carries are condensed out. This liquid condensate is caught by 55 the basin formed by the lower deflector 43 and continuously withdrawn through the drain 46. After passing through or over the pipe-coil 45 the air current enters the lower ends of the tubes 42 and in traversing 60 the latter is partially re-heated by exchange of heat with the entering air. It then passes to the superheater, enters the drying chamber and completes its cycle in the manner above described.

In Fig. 5 I have illustrated another modi-

fied form of the apparatus arranged for use in an ordinary manner without resorting to circulation of the drying medium. This apparatus is identical with that described in Fig. 1 save that the outlet 20 of the collector 70 is connected to an elbow 50 and thence to any suitable discharge conduit leading away from the apparatus. Similarly, another elbow 51 serves to connect an inlet conduit with the base of the heater. In the construction shown in Fig. 5, therefore, atmospheric air or other gas is admitted to the apparatus, as shown, passes through the heater, where its temperature is raised and its capacity for absorbing or carrying off 80 liquid vapors increased, is then introduced into the drying chamber, passes through the latter and through the fan and cyclone collector, and is discharged from the system.

While I have in the foregoing described in 85 considerable detail several specific embodiments of my invention, it will be understood that this is illustrative only and for the purpose of making the invention more clear and that the invention is not limited to these details nor to any of them except in so far as such limitations form a part of the accompanying claims, in which it is my intention to claim all novelty inherent in the invention as broadly as is permissible in view of the 90 prior art.

What I regard as new and desire to secure by Letters Patent is:

1. In combination with a vertical drying chamber, a centrifugal fan mounted below 100 the said chamber and with its axis vertical, the central axial inlet of the fan forming the bottom of the said chamber, a vertical cyclone dust collector mounted in proximity to the said fan, and a communication duct 105 forming the tangential outlet of the said fan and the tangential inlet of the said cyclone dust collector.

2. A circulatory spray desiccation apparatus comprising a vertically disposed drying chamber, a centrifugal fan at the base of the said chamber, the central axial inlet of the fan forming the bottom of the chamber, a vertical cyclone collector in close proximity to the fan, a horizontal duct connecting the fan and cyclone collector and forming a tangential outlet for the former and a tangential inlet for the latter, a vertical duct connected with the cyclone collector outlet at the lower end and with the upper 120 end of the drying chamber, and means for heating the circulating medium located within the said duct.

3. A circulatory spray desiccation apparatus comprising a vertically disposed drying chamber, a centrifugal fan at the base of the said chamber, the central axial inlet of the fan forming the bottom of the chamber, a vertical cyclone collector in close proximity to the fan, a horizontal duct con- 125

necting the fan and cyclone collector and forming a tangential outlet for the former and a tangential inlet for the latter, and a vertical duct connected with the cyclone collector outlet at the lower end and with the upper end of the drying chamber.

4. The combination with a vertically disposed cyclone dust collector, of a centrifugal blower having its shaft arranged vertically and in close proximity to the said collector,

and a horizontal duct forming the tangential outlet of the fan and the tangential inlet of the said collector, the axis of said duct having a curvature in the same direction as that of the fan casing, whereby the initial separation obtained within the fan is maintained through the duct and into the cyclone collector. 15

HANS J. ZIMMERMANN.
